FELLING MACHINE COMPANY, OF BOSTON, MASSACHUSETTS, A CORPORATION
OF MAINE.

WORK-PRESENTING MECHANISM FOR SEWING-MACHINES.

1,333,310.

Specification of Letters Patent.

Patented Mar. 9, 1920.

Application filed July 10, 1916. Serial No. 108,279.

To all whom it may concern:

Be it known that I, THOMAS J. HAYES, a citizen of the United States, and resident of Roslindale, county of Suffolk, State of Massachusetts, have invented an Improvement in Work-Presenting Mechanism for Sewing-Machines, of which the following description, in connection with the accompanying drawing, is a specification, like characters on the drawing representing like parts.

This invention relates to improvements in work presenting mechanism for sewing machines and the principal object thereof is to provide a simplified bender mechanism which will be easy of construction, sure in operation and accurate in adjustment.

In order properly to present the goods to the needle the bender must be elevated to the proper height upon each movement. Otherwise the stitch taken in the work will be too shallow or too deep and any looseness or wear of the bender operating parts will result in the improper operation of the bender. One of the objects of the invention therefore is to provide a bender of a rigid character which may be readily and accurately adjusted.

This is accomplished in the present invention by providing a bender which preferably is supported rigidly upon a pivoted bender supporting member, suitable mechanism being provided for operating the same but adapted to permit the bender to yield when an obstruction is encountered.

The bender supporting member preferably is in the form of a relatively long arm carrying at one end a bender and supported at its opposite end upon a pivot located at a considerable distance from the bender, preferably along the longitudinal axis of the machine, the pivot desirably being so located that the movement of the bender will be substantially normal to the surface of the bed plate.

Another object of the invention is to provide means whereby the height of the bender may be accurately adjusted preferably combined with means providing a yielding connection between the bender supporting arm and its actuating mechanism.

Another object of the invention is to provide guiding means for the bender which

will prevent any lateral vibration thereof and which may be quickly adjusted to take up wear.

In designing bender mechanism, particularly for use in blind stitch sewing machines in which the needle and complementary stitch forming mechanism is located and operated from above the bed plate of the machine considerable difficulty has been encountered in providing means for withdrawing the bender an adequate distance and with sufficient rapidity to avoid the moving feed dog when a thick seam is passing between the work support and the presser foot.

This is particularly difficult where the bender is elevated at every other oscillation of the needle as in usual forms of blind stitch felling machines since the bender actuating cam is revolving only at half the speed of revolution of the cams which actuate the feeding mechanism.

Another object of the present invention is to provide a mechanism which will quickly raise and lower the bender sufficiently to avoid the feed dog under all conditions of work. This is accomplished in the present embodiment of the invention by providing a cam having a dwell to sustain the bender during the penetration of the needle, the cam being actuated by a variable speed motion which will cause the rapid raising and lowering of the bender supporting member.

Another object of the invention is to provide a bender actuating mechanism which can readily be modified to cause the bender to be actuated upon each stroke of the needle, as is customary in padding or upon alternate strokes as is usual in blind stitching for felling. This is accomplished in the preferred embodiment of the invention illustrated herein by providing certain adjustable bearings for a divided bender shaft having its sections out of alinement and connected by means adapted to transform a constant movement of one portion of said shaft into a variable movement for the other or cam actuating section of the shaft, said adjustable bearings permitting the sections of the shaft to be placed in alinement when the bender is to be actuated upon each oscillation of the needle as in padding.

This will permit the use either of a straight shaft, adapted to actuate the bender upon each reciprocation of the needle or a divided shaft having its sections offset to accommodate gears adapted to cause one revolution of the main shaft and to provide means whereby the shafts may be so coupled together as to give the bender actuating cam a variable speed of revolution for the purpose above set forth.

Another object of the invention is to provide a construction adapted more easily to be assembled and adjusted than has heretofore been accomplished in order to save the labor of machining.

Other objects of the invention will more fully appear from the following description and the accompanying drawings and will be pointed out in the annexed claims.

20 In the drawings:

Figure 1 is a side elevation of a blind stitch sewing machine embodying an illustrative form of my invention.

Fig. 2 is a bottom plan view of a sewing machine bed plate illustrating a preferred form of bender actuating mechanism in which the bender is adapted to be actuated upon every alternate oscillation of the needle.

30 Fig. 3 is a longitudinal sectional view of the same.

Fig. 4 is a bottom plan view of a portion of a similar bender mechanism adapted to actuate the bender upon every oscillation of the needle,

Fig. 5 is a detail view of the bender actuating cam,

Fig. 6 is a detail view showing the sections of the bender shaft connected by a sleeve,—an alternative construction to that illustrated in Fig. 4.

Fig. 7 is a detail view of the adjusting mechanism for the bender.

The present invention is illustrated herein as embodied in a blind stitch sewing machine of the Arbetter type having a bed plate 1 preferably provided with an upwardly projecting boss 2 forming a base for the standard 3 which carries the usual overhanging arm 4 and head 5. The main shaft 6 is journaled in suitable bearings in the arm and is driven by a pulley 7 which may be clamped firmly upon the shaft by the screw 8 or released therefrom sufficiently 55 to permit the pulley to run free in bobbin winding.

The needle actuating mechanism preferably is carried by the head and as illustrated herein comprises a needle supporting arm 9 pivotally mounted upon a stud 10 in the upper portion of the head of the machine, the lower end of the needle supporting arm 9 being bifurcated to provide journals 11 for a needle bar 12 carrying a curved 65 needle. The needle bar is oscillated through

a link 13 suitably actuated from the main shaft and connected to an arm 14 of the needle bar. Lateral or shogging movement may be imparted to the needle through a cam 15 connected by a link 16 to the needle supporting arm 9, said cam being driven by a gear 17 actuated by a companion gear 18 upon the main shaft.

Any suitable take-up mechanism may be provided for the purpose of setting the stitch. The complementary stitch forming mechanism preferably is in the form of a rotary loop taker or hook supported in the hook bracket 19 depending from the head of the machine. The hook bracket also preferably carries a presser foot 20 which is adapted to coöperate with a vertically movable work support 21 preferably of the character used in the Arbetter type of machines and which need not be illustrated herein as it forms no essential part of the present invention.

In such constructions the presser foot and feed dog are alternately reciprocated toward and from the stationary presser foot which is carried by the head of the machine and it is therefore necessary for the bender mechanism to be given such a movement as to permit the proper movement of the feed dog without interference even though the work support and feed dog are depressed a considerable distance by the passage of a thick seam or when operating upon thick goods.

It is also essential under such conditions that the bender be raised and lowered quickly to enable it to clear the path of the feed dog.

The present form of bender mechanism illustrated herein is particularly adapted to accomplish this result.

In the preferred embodiment of the invention illustrated herein the bender 22 is rigidly secured to one end of a bender supporting member or arm 23 which is pivoted at its opposite end upon a shaft or pin 24 preferably mounted in the boss 2 which extends upwardly from the bed plate, the pivotal axis of the bender supporting member 23 desirably being so located that the movement of the work engaging end of the bender will be substantially normal to the plane of the bed plate and work support. The bender 22 preferably is L-shaped, the extension 25 being secured rigidly by screws 26 to the end of a bender supporting member 23. Suitable dowel pins 27 may also be provided to prevent any possible movement of the bender relatively to the arm.

The bender supporting member 23 is actuated through a reciprocating member which is yieldably connected to the bender supporting arm to permit yielding movement of the bender in case its end meets an obstruction in the work, such as a thick seam. Any

suitable reciprocating mechanism may be yieldably connected to the bender. The preferred mechanism illustrated herein however comprises a lever 28 pivotally mounted 5 at one end, preferably upon the same shaft 24 as that which constitutes the pivot for the bender supporting member 23.

The bender actuating lever 28 is provided at its opposite end with a boss 29 in which 10 an adjusting screw 30 is seated said adjusting screw having an extension 31 of decreased diameter which passes freely through an aperture in an ear 32 extending laterally from the bender supporting 15 lever 23.

The lower end of the threaded portion of the screw 30 provides a shoulder 33 which may be adjusted downwardly to engage the ear 32 upon the bender supporting member and 20 serve as an adjustment for the height to which the bender may be raised so that the bender may be adjusted for different thicknesses of goods. The uppermost elevation of the bender is limited by the contacting 25 of the boss 29 with the ear 32 so that the bender cannot be raised enough to injure the needle.

This yieldable connection between the bender supporting member and the bender 30 actuating lever may be located in any desirable position but preferably is in proximity to the bender, as between the bender and the mechanism which actuates the bender supporting lever. In such construction the bed 35 plate may be provided with a cup shaped recess 34 through which the end of the adjusting screw 30 may extend when the bender is in elevated position and the screw 30 may be provided with a knurled nut 35 by which 40 it may conveniently be adjusted by the operator.

The reciprocable member or lever 28 may be actuated in any suitable manner but preferably is operated by a cam 36 mounted 45 upon a bender actuating shaft 37 extending transversely of the machine and carried by bosses 38 and 39 depending from the under surface of the bed plate.

The lever 28 preferably is provided with 50 laterally extending ears or flanges 40, 41 to which wear plates 42 and 43, adapted to engage the cam 36, are secured. The cam 36 preferably has an extended hub 44 which is secured to the shaft by suitable set screw or 55 a tapered pin 45. The bender actuating shaft 37 is rotated through a train of gears comprising a miter gear 46 having a hub 47 suitably secured to the shaft 37 and a co-operating gear 48 carried by a counter shaft 60 extending longitudinally of the bed plate of the machine.

For convenience in assembling and in taking up wear the bosses 38 and 39 are bored 65 to receive bushings 50 which are adjustably secured in said lugs by screws 51. In as-

sembling the machine the bender actuating shaft 37 with the cam 36 and beveled gear 46 thereupon is inserted in the bushings, the cam is then located properly beneath the ear 40 on the lever 28 and the set screw in its hub 44 tightened. The miter gear 46 is then adjusted upon the shaft until it runs freely with the gear 48 whereupon it is rigidly secured to the shaft and the bushing members 50 are then pressed tightly against the outer 75 hubs of the cam and the miter gear 46 respectively so that longitudinal movement of the shaft 37 is absolutely prevented. By this arrangement the necessity for accurate drilling and machining of the boss is 80 rendered unnecessary and convenient means provided for repairing the worn out parts since the bushings 50 may accurately be adjusted inwardly to take up for the wearing of the gears and when bushings are worn 85 out they may easily be replaced.

In order to prevent lateral movement of the bender mechanism a guide is provided which preferably embraces the bender supporting arm 23 and its actuating lever 28. 90 This guide preferably is located between the bender actuating device and the free end of the bender supporting member. A preferred form of guide which is illustrated herein comprises a pair of plates 52 one of 95 which is secured to the under surface of the bed plate by suitable screws and dowel pins and the other of which is adjustably secured to the bed plate by a screw and slot connection, each of said plates being provided with upwardly extending ears 52^x which are connected together by a bolt 53 extending through suitable slots in the bender supporting arm 23 and its actuating lever 28. The bender supporting lever and bender 100 actuating lever preferably are provided with thickened portions or bosses 23^x and 28^x which may be easily and economically machined to provide guiding surfaces to engage the ears 52^x of the guide plates and also 110 to engage each other.

In view of the fact that blind stitching machines are used mainly for felling and for padding it is desirable that the essential parts of the machine be so constructed that 115 in its manufacture the same bed plate and superstructure may be used as in the manufacture of machines for either kind of work. The present embodiment of the invention is illustrative of a convenient construction by 120 which either a padding machine or a felling machine may be made, or in fact one type of machine transformed into the other by a mere adjustment of parts and the substitution of suitable gears for driving the bender 125 actuating shaft to actuate the bender in co-operative relation to the needle for the character of work desired.

In padding the bender is actuated to raise the goods into the path of the needle upon 130

each stitch and consequently operates in synchronism with the needle and feed dog mechanisms so that the cam above described alone will serve to withdraw the bender from 5 the path of the feed dog.

In felling work, however, in which a superimposed layer is sewed to a base layer of material the bender is actuated upon alternate thrusts of the needle to present the 10 base layer in its path and consequently there are two movements of the feed dog to one movement of the bender. It is therefore desirable if not absolutely essential that the bender be withheld from the path of the 15 feed dog during one set of stitches and consequently that it be given a very rapid raising and lowering movement to thrust the work into the path of the needle upon alternating sets of stitches, time however being 20 provided for the needle to pass through the work and across the opening in the presser foot before the bender is withdrawn, otherwise the tension upon the cloth is likely to cause the point of the needle to pass beneath 25 a portion of the presser foot, thus causing the breakage of the needle.

In order to accomplish this result the bender cam is provided with a dwell of sufficient extent to sustain the bender in its 30 elevated position the required amount of time, the cam being given a variable speed of rotation which will speed up quick raising and lowering movement above described.

A preferred form of cam which is illustrated in Fig. 5 of the drawing comprises an extended low portion *a*, relatively steep portions *b* and a dwell *c*. The cam may be given a variable speed of rotation in any suitable manner but conveniently is driven 40 by a divided counter shaft consisting of sections 55 and 56 the section 55 being mounted in brackets 57, 58 secured to the bed plate and the section 56 being mounted in adjustable brackets 59 and 60, the process of which 45 adjustment will be hereinafter described.

The counter shaft sections 55 and 56 desirably are located in the same horizontal plane below the surface of the bed plate but are offset from one another and connected 50 by means through which the constant rotation of the shaft 56 will cause a variable speed of rotation of the shaft 55. This mechanism as illustrated herein comprises arms 61 and 62 rigidly secured by pins 63 and 64 respectively to the ends of the shafts 55 and 56, the ends of the arms being connected by a link 65.

In order to provide means for taking up wear at the pivots of the link 65 with the 60 arms 61, 62, the arms 61—62 are provided at their ends with bosses having screw threaded apertures and the ends of the link 65 are likewise provided with bosses having tapered apertures. Pivotal screws having conical surfaces 66 and cylindrical screw threaded

shanks are passed through the bosses in the link 65 and screwed into the bosses in the ends of the arms 61 and 62 and are then tightened sufficiently to make an easy running fit whereupon nuts 68 are screwed 70 tightly against the ends of the bosses to lock the screws from movement. If any wear takes place the screws 66 may be tightened in an obvious manner.

The shaft 56 may be rotated in any convenient manner preferably through a gear 69 which meshes with a gear 70 upon a shaft 71 which is provided at its upper end with a suitable gear 72 meshing with a gear 73 upon the main shaft 6. 75

The gears 72 and 73 may be of equal diameter and when the machine is arranged for felling as illustrated herein the gears 70 and 69 will be so proportioned as to cause one rotation of the shaft 56 to every rotation 85 of the main shaft 6 so that the bender will be raised and lowered upon alternate stitches as above described while the variable movement will cause the desired rapid elevation and depression of the bender. In such case 90 the gears 69 and 70 are provided respectively with teeth arranged at an angle of 60 and 30 degrees to the central plane of the gear.

When it is desired to utilize the machine for padding the adjustable bearings 59 and 60 may be removed from the positions illustrated in Fig. 2 and placed in alinement to accommodate a straight shaft 75 such as is illustrated in Fig. 4 in which case it may be only necessary to use the extreme bearings 100 57 and 60. Alternatively however, the divided counter shaft may be utilized by removing the arms 61 and 62 and the connecting link 65 and connecting the sections 56 and 55 of the divided shaft by a suitable 105 sleeve 76 as is illustrated in detail in Fig. 6.

In the latter case the gears 69 and 70 which are provided respectively with teeth of 30 and 60 degrees inclination to the vertical plane of the gear will be removed and gears 110 of equal diameter having teeth arranged at an angle of 45 degrees to the plane of the gear will be substituted.

By such construction the machine may be readily transformed from a felling machine into a padding machine or vice versa according to the requirements of the operator or either machine may be constructed in the factory with minimum cost of labor and material. 115

In order further to reduce the cost of manufacture and upkeep the bearings 57 and 58 and 59 and 60 may be constructed as brackets adapted to be secured to the bed plate of the machine and any or all of said bearings 120 may be provided with removable bushings 77 adjustably secured therein by set screws 78. This will materially aid in assembling of the machine since the shaft may be installed and the bushings thrust against the 125 130

hubs or shoulders of the gears and arms in such a manner as to prevent all endwise movement of the shaft.

Furthermore, when the machine has been 5 used any wear may be taken up by adjusting these bushings.

It is to be understood that the embodiment 10 of the invention herein described is illustrative and not restrictive and that various modifications may be made or equivalent structures substituted within the meaning of the following claims.

Having thus described my invention what I claim as new and desire to secure by Letters Patent is:

1. Work presenting mechanism for sewing machines comprising a bender, a pivotally mounted bender supporting member, a reciprocable member, means for actuating 20 the same, and means located intermediate of said bender and its pivotal support yieldably connecting said bender supporting member and said reciprocable member.

2. Work presenting mechanism for sewing 25 machines comprising a bender, a pivotally mounted bender supporting member, a reciprocable member located adjacent to and lying in parallelism with said bender supporting member, means for actuating said reciprocable member, and means located intermediate of said bender and said actuating means yieldably connecting said bender supporting member and said reciprocable member.

3. Work presenting mechanism for sewing 35 machines comprising a bender, a pivotally mounted bender supporting member, a reciprocable member located adjacent to and lying in parallelism with said bender supporting member, means for actuating said reciprocable member and means located in proximity to said bender yieldably and adjustably connecting said bender supporting means and said reciprocating member.

45 4. Work presenting means for sewing machines comprising a bender, a pivotally mounted bender supporting member rigid therewith, a bender actuating lever, means yieldably connecting said bender supporting member to said bender actuating lever, a cam engaging the latter and means for actuating said cam.

55 5. Work presenting means for sewing machines comprising a bender, a pivotally mounted bender supporting lever rigid therewith, a bender actuating lever lying in parallelism with said bender supporting lever, means yieldably and adjustably connecting said bender supporting lever to said bender actuating lever, a cam engaging the latter and means for actuating the cam.

60 6. Work supporting mechanism for sewing machines comprising a bender, a bender supporting member and a bender actuating lever pivotally mounted upon the same axis,

means for reciprocating said lever and yieldable means connecting the said actuating lever to said bender supporting member.

7. Work presenting mechanism for sewing 70 machines comprising a bender, a pivotally mounted bender supporting member, a bender actuating lever, means yieldably connecting said bender supporting member to said lever, a cam having a dwell engaging said lever and means for rotating said cam, 75 whereby the bender will be quickly raised and lowered and caused to dwell during the penetration of the needle.

8. Work presenting mechanism for sewing 80 machines comprising a bender, a pivotally mounted bender supporting member, a bender actuating lever, means yieldably connecting said bender supporting member to said lever, a cam having a dwell engaging said lever, and means for imparting a 85 variable movement to said cam whereby the period of dwell of said cam will be prolonged.

9. Work presenting mechanism for sewing 90 machines comprising a bender, a pivotally mounted bender supporting member, a bender actuating lever, means yieldably connecting said bender supporting member to said lever, a cam having a dwell engaging said lever, and means including a counter-shaft having connected differentially rotatable sections for imparting a variable movement to said cam whereby the period of dwell of said cam will be prolonged. 95

10. In a blind stitch sewing machine comprising a bed plate, and stitch forming mechanism including an oscillating needle bar located above the bed plate, work presenting mechanism including a bender, a pivotally mounted bender supporting lever 105 extending longitudinally of the bed plate, a reciprocable member yieldably and adjustably connected to said bender supporting member and means for actuating said reciprocable member. 100

11. In a blind stitch sewing machine comprising a bed plate, and stitch forming mechanism including an oscillating needle bar located above the bed plate, work presenting mechanism including a bender, a pivotally mounted bender supporting lever 115 extending longitudinally of the bed plate, a reciprocable member yieldably and adjustably connected to said bender supporting member and adapted to be adjusted from above the bed plate and means for reciprocating said reciprocable member. 120

12. In a blind stitch sewing machine comprising a bed plate and stitch forming mechanism including an oscillating needle 125 bar located above the bed plate, work presenting mechanism including a bender, a pivotally mounted bender supporting lever extending longitudinally of the bed plate, guiding means for said bender supporting 130

member located in proximity to the bender, a reciprocable member, means yieldably connecting said bender supporting member and said reciprocable member and means for actuating the latter.

13. In a blind stitch sewing machine comprising a bed plate, and stitch forming mechanism including an oscillating needle bar located above the bed plate, work presenting mechanism including a bender, a bender supporting member and a bender actuating lever pivotally movable about the same axis and extending in parallelism longitudinally of the bed plate of the machine, means yieldably connecting said bender supporting member and said lever, guiding means engaging said bender supporting member and said bender actuating lever in proximity to said bender, and means for reciprocating the bender actuating lever,

14. In a blind stitch sewing machine comprising a bed plate, and stitch forming mechanism including an oscillating needle bar located above the bed plate, work presenting mechanism including a bender, a bender supporting member and a bender actuating lever pivotally movable about the same axis and extending in parallelism longitudinally of the bed plate of the machine, means yieldably connecting said bender supporting member and said lever, guiding means engaging said bender supporting member and said bender actuating lever in proximity to said bender, a cam having a dwell, mounted upon a transverse shaft and engaging said bender actuating lever and means for rotating said cam.

15. In a blind stitch sewing machine comprising a bed plate, and stitch forming mechanism including an oscillating needle bar located above the bed plate, work presenting mechanism including a bender, a bender supporting member and a bender actuating lever pivotally movable about the same axis and extending in parallelism longitudinally of the bed plate of the machine, means yieldably connecting said bender supporting member and said lever, guiding means engaging said bender supporting member and said bender actuating lever in proximity to said bender, a cam having a dwell, mounted upon a transverse shaft and engaging said bender actuating lever and means for imparting a variable speed of rotation to said cam whereby a quick elevation and depression of the bender will be produced.

16. In a blind stitch sewing machine comprising a bed plate, and stitch forming mechanism including an oscillating needle bar located above the bed plate, work presenting mechanism including a bender, a pivotally mounted bender supporting member extending longitudinally of the bed plate, a cam for raising and lowering said

bender supporting member, means for rotating said cam including a divided countershaft consisting of two sections extending in parallelism, one of said sections being operatively connected to said cam, driving means for the other section and means connecting said shaft sections adapted to impart a variable speed of rotation to the cam.

17. In a blind stitch sewing machine comprising a bed plate, and stitch forming mechanism including an oscillating needle bar located above the bed plate, work presenting mechanism comprising a bender supporting member having a bender rigidly connected at one end and mounted at its opposite end upon a pivot located above the bed plate, whereby the path of the bender when engaging the work will be substantially normal to the plane of the surface of the bed plate and means for actuating said bender supporting member.

18. In a blind stitch sewing machine comprising a bed plate, a standard rising therefrom having an arm, a head overhanging the bed plate, and stitch forming mechanism including an oscillating needle bar carried by said head, work presenting mechanism including a bender supporting lever having a bender rigidly secured at one end and mounted at its opposite end upon a pivotal support within said standard and above the plane of the base plate whereby the path of the bender when engaging the work will be substantially normal to the plane of the surface of the bed plate and means for actuating said bender supporting member.

19. In a blind stitch sewing machine comprising stitch forming mechanism, work presenting mechanism including a bender, a bender actuating shaft, a countershaft having one section connected to said bender actuating shaft and means for driving the other section of said countershaft, means for adjusting one of the sections of said countershaft to permit the use of different gears whereby the timing of the bender for different kinds of work may be varied.

20. In a blind stitch sewing machine comprising a bed plate, and stitch forming mechanism including an oscillating needle bar located above the same, work presenting mechanism including a bender, a bender supporting member, a bender actuating shaft supported in bearings secured to the bed plate, a countershaft and means for actuating the same, intermeshing gears upon said bender actuating shaft and said countershaft and means for adjusting certain of the bearings for said bender actuating shaft to permit the use of gears of different diameter upon said bender actuating shaft and said countershaft whereby the timing of the bender may be varied for different kinds of work.

21. In a blind stitch sewing machine com-

- prising a bed plate, and stitch forming mechanism including an oscillating needle bar located above said bed plate, a bender, a bender actuating shaft, a divided countershaft supported in bearings secured to said bed plate, a main shaft, means for actuating said countershaft from said main shaft, intermeshing gears upon said bender actuating shaft and said countershaft, means for adjusting the bearings of one section of said countershaft to permit the use of alternative gears upon the bender actuating shaft and the countershaft and, interchangeable means for connecting the sections of the divided countershaft whereby the bender actuating shaft may be given alternatively a uniform speed of rotation or a variable speed of rotation. 65
22. In a blind stitch sewing machine comprising a bed plate, stitch forming mechanism including an oscillating needle bar located above the bed plate, a bender supporting member having a bender connected at one end and mounted at its opposite end 70
- 25 upon a pivot located above the surface of the bed plate, a bender actuating lever mounted upon the same pivot and extending in parallelism to and yieldably connected with said bender supporting member, a cam mounted 75
- 30 upon a transverse shaft engaging said bender actuating lever, a counter shaft extending longitudinally of the machine and connected by gearing to said transverse shaft, a main shaft, a means for actuating 80
- 35 said countershaft from said main shaft, intermeshing gears upon said countershaft and said transverse shaft and means for adjusting certain of the bearings of said countershaft to permit the use of gears of different diameter and different pitch upon 85
- 40 said transverse shaft and countershaft whereby the timing of the bender may be varied for different kinds of work. 90
23. In a blind stitch sewing machine comprising a bed plate, and stitch forming mechanism including an oscillating needle bar located above the bed plate, a pivoted bender supporting member extending longitudinally of the bed plate, a bender actuating lever extending in parallelism with and adjacent thereto and yieldably connected thereto, bearing surfaces upon said bender supporting member and said lever and adjustable guiding means engaging said 95
- 50 bender supporting member and said lever opposite said bearing surfaces, to prevent lateral vibration of the bender. 100
24. In a blind stitch sewing machine, work presenting mechanism including a bender supporting member having a lateral exten- 105
- 55 sion and a reciprocable bender actuating member having an extension overlying the extension upon the bender supporting member, an adjusting screw seated in one of said extensions and having a shoulder adapted to engage the other extension and resilient means adapted to force said extensions toward each other whereby the bender supporting member will be caused normally to move in unison with said actuating member but will yield relatively thereto when the bender 60 encounters an obstruction. 110
25. In a blind stitch sewing machine, work presenting mechanism including a bender supporting member having a lateral extension and a reciprocable bender actuating member having an extension overlying the extension upon the bender supporting member, an adjusting screw seated in one of said extensions having a stem passing freely through the other extension and a helical spring carried by said stem abutting against the latter extension adapted to force said extensions toward each other. 115
26. In a sewing machine comprising a bender and means for actuating the same including a shaft, a cam on said shaft, a gear on said shaft and means for rotating the same, bearings for said shaft including longitudinally adjustable bushings adapted to engage respectively the hubs on said cam and gear, whereby assembling of the mechanisms is facilitated and means provided for compensating for wear. 120
27. In a sewing machine comprising a bender and means for actuating the same including a shaft provided with actuating instrumentalities having hubs presenting flat faces of greater diameter than that of the shaft, bearings for said shafts having adjustable bushings adapted to be forced into engagement with the faces of said hubs and thereby to prevent longitudinal movement of said shaft, whereby the assembling of the parts of the mechanisms is facilitated and means provided for compensating for wear. 125
28. Work presenting mechanism for sewing machines comprising a bender, a pivoted bender supporting member, a bender actuating member yieldably connected thereto and having a cam fork, a cam within said fork continuously engaging the members thereof, said cam having a dwell to sustain the bender during the penetration of the needle and curved surfaces adapted to cause a quick elevation and depression of said bender. 130

In testimony whereof I have signed my name to this specification.

THOMAS J. HAYES.
